UNITED STATES PATENT OFFICE.

HURGAR HUNNICUTT, OF MALVERN, ARKANSAS.

AERIAL SHIP.

SPECIFICATION forming part of Letters Patent No. 334,866, dated January 26, 1886.

Application filed August 7, 1885. Serial No. 173,858. (No model.)

To all whom it may concern:

Be it known that I, HURGAR HUNNICUTT, a citizen of the United States of America, residing at Malvern, in the county of Hot Springs and State of Arkansas, have invented 5 certain new and useful Improvements in Aerial Ships, of which the following is a specification, reference being had therein to the accompanying drawings.

10 My invention consists of certain improvements in aerial ships or vessels and machinery for propelling and managing the same, as follows:

First. A sharp pointed elongated and cylindrical-shaped balloon with a car for carrying passengers and machinery attached, as shown by the accompanying drawings, Figure 1.

Second. It consists of two screw-propellers, as shown in Fig. 2, and hereinafter described.

20 Third. Of certain arrangements of metallic tubes or pipes and shafting, as shown in Fig. 3, and hereinafter described.

Fourth. Managing the direction of the pulling power of the screw-propellers as shown 25 in Fig. 4, and hereinafter described.

Fifth. Of an automatic valve for the purpose of maintaining or keeping the equilibrium between the lifting power of the balloon and the attraction of gravitation.

30 Sixth. Of a rail having an arm on either attached to base-rail of the balloon.

It also consists of an arrangement whereby the car is adjustable backward and forward, in order that the center of gravity of the car can 35 be kept under the center of the lifting power of the balloon, thereby maintaining a horizontal position, all of which is more fully explained in the following specification, reference being had to the accompanying drawings.

40 Fig. 1 is a complete air-ship, side view. 1 shows the position of the automatic gas-valve. 2 is a rope running around three pulleys, 3, one at either end and one in the center. The two end pulleys run on the bar i.

45 3 is the center pulley aforementioned, having two grooves, in one of which rope 2 runs. 4 is a rope passing from pulleys 3 to a pulley, 5, or wheel below, which is attached to the car. 5 is a wheel or pulley having a crank attached, the

50 turning of which causes rope 4 to turn pulley 3, which pulls rope 2, thereby moving the car backward or forward, as desired by the aero-

naut. 6 is a lever hinged to the car on a pivot, which is attached at its upper extremity to the propelling power, by which means the propelling power can be raised or lowered for the purpose of bringing it to the center of resistance between the car and the balloon. 7 is a lever, by the action of which the direction of the pulling power of the propellers is changed at will. 8 is a beveled gear-wheel which is firmly fastened on the end of the main shaft 12, and meshes with a similar wheel on the shaft of the screw-propeller. 9 is a beveled gear-wheel fastened on the end of the shaft of the 65 propeller, and meshes with one of a similar kind on the main shaft. 11 is a rudder working on a universal joint at the rear extremity of the car. The aforesaid car and balloon are to be made of any material that is found suitable. 70

Fig. 2 is a top view of the car. 12 is the main shaft that drives the propellers. 8 are beveled gear-wheels, which are fastened on the main shaft 12, which mesh with similar wheels, 9, on the shaft of the propellers. 9 75 are beveled gear-wheels fixed on the shafts 10 of the propellers. 10 are the shafts of the propellers. 13 are steel arms through which pass the shafts of the propellers at a. 14 is a metal tube through which passes another tube, 80 16, and the main shaft 12. 15 is a connecting-arm, which is firmly fastened to the tubes 14 at b by an adjustable joint, which makes the said tubes practically continuous for strength from 13 to 13, where they terminate, but are 85 not fastened to arms 13. 16 are metal tubes which are inside of the tubes 14, and through which passes the main shaft 12, and they (the tubes 16) are firmly fixed to arms 13 at c. 17 are gear-wheels fixed on tubes 16. g is a pulley on main shaft, which is to be so arranged 90 as to be either fixed or loose at pleasure by any known method.

Fig. 3 is a sectional view of the tubing 14 and 16 and main shaft 12. 18 are journal-bearings between main shaft 12 and tubes 16. 95 19 are journal-bearings between tubes 16 and tubes 14.

Fig. 4 is a part of the car with levers 6 and 7, as shown in Fig. 1, attached. 17 is one of two gear-wheels attached to tubes 16, as per Fig. 2. 6 is one of two levers which are attached to tubes or pipes 14 at their inner ends, and are pivoted at h to the car on its inside,

and is for the purpose of raising the entire propelling power, as above described. By moving lever 7, as shown in Figs. 1 and 4, gear-wheel 17 is turned, thereby turning tubes 5 16, which carry with them arms 13, which carry the propellers, so that by pulling lever 7 the propellers can be made to pull backward, forward, upward, downward, or in any direction, thereby carrying the ship in any direction desired.

Fig. 5 is a part of the body of the balloon, with braces 27 attached, holding a barometer, 24, and also showing a brace or bracket, *f*, having a lever, 26, pivoted therein, one end 15 being fastened to a valve, *e*, and the other connected with the barometer 24 by means of magnetism.

Fig. 6 is a cross-sectional view of the rail *i* and base-rail of the balloon. 24 is a barometer. 20 25 is cylindrical block of steel loosely fitting in the said barometer. 26 is a lever, of magnetized steel, having its positive pole *e*² toward said block of steel 25. The other end of said lever is made fast to said valve at *e*. Now, as the air 25 ship or vessel ascends the mercury sinks and carries with it the said block of steel 25, and it in turn carries with it the positive end of lever 26, thereby opening the valve *e*, the lever being pivoted to bracket *f*, and when the air- 30 ship goes down the mercury rises and carries with it the said block and the lever aforementioned, and thereby closes said valve. Now, the object of this valve is to keep up the equi- 35 poise between the lifting power of the gas and the weight lifted, so as to make it travel at any given height.

Having described my invention in aerial navigation, what I claim as new, and desire to secure by Letters Patent, is—

40 1. In an aerial ship as above described, the combination, with the balloon, of the car attached to the said balloon by means of the end pulleys, 3, running on the rail *i* at the base of the balloon, and pipes attached thereto and 45 to said car, rope 2, attached to said end pulleys and passing around the center pulley, 3,

and rope 4, passing around said center pulley, 3, and pulley 5, substantially as shown and described, and for the purposes set forth.

2. In combination with the car of an aerial 50 ship as above described, the main shaft 12, running crosswise the bow of said car and extending beyond either side, and having on either end journal-bearings 18 and beveled gear-wheels 8, and on its center a pulley, *g*, the 55 tubes or hollow shafts 16, having journal-bearings 19 and running on either end of said main shaft 12, and bearing on their outer ends the elbow-arms 13, which bear the propellers, and beveled gear-wheels 9, meshing with said 60 beveled wheels 8, and on their inner ends a gear-wheel, 17, rigidly attached to the same, lever 7, pivoted to lever 6, its fulcrum end having teeth meshing with said wheel 17, connecting-arm 15, having securely clamped in either 65 end outside pipes, 14, all substantially as shown and described, and for the purposes set forth.

3. In an aerial ship as above described, the combination of the levers 6, pivoted to the 70 inside walls of the car by bolts *h*, their fulcrum ends encircling pipes 14, and adapted to raise the propelling power, as shown, and levers 7, pivoted to the right-angle arm of said levers 6, their teeth on their fulcrum ends meshing 75 with gear-wheels 17, substantially as shown and described, and for the purposes set forth.

4. In an aerial ship as above described, the combination, with the balloon, of bracket *f*, lever 26, pivoted in said bracket, valve *e*, attached to the negative end *e*² of said lever, its positive end *e*² extending to barometer 24, barometer 24, bearing on its mercury a magnetic steel block, 25, substantially as and for the purposes set forth. 80 85

In testimony whereof I affix my signature in presence of two witnesses.

HURGAR HUNNICUTT.
